UNITED STATES PATENT OFFICE.

JAMES ROCHE, OF TERRYVILLE, CONNECTICUT, ASSIGNOR TO THE EAGLE
LOCK COMPANY, OF SAME PLACE.

DESIGN FOR A PADLOCK.

SPECIFICATION forming part of Design No. 24,584, dated August 20, 1895.

Application filed June 17, 1895. Serial No. 553,140. Term of patent 7 years.

To all whom it may concern:

Be it known that I, JAMES ROCHE, of Terryville, in the county of Litchfield and State of Connecticut, have invented a new Design 5 for a Padlock; and I do hereby declare the following, when taken in connection with the accompanying drawing and the letters of reference marked thereon, to be a full, clear, and exact description of the same, and which 10 said drawing constitutes part of this specification, and represents a view in side elevation of a padlock containing my improved design.

My invention relates to a design for a padlock; and the design consists in the configuration as hereinafter described, and shown in 15 the accompanying illustration.

As herein shown the design consists in a padlock having an oblong body A, shaped to form a rounded outer end A', a concaved inner end A'', and slightly-tapering sides A³, which converge from its outer to its inner 20 end. The shackle B conforms in external curvature to the outline of the body, which it virtually continues so as to form an oblong

figure having rounded ends and slightly-tapering sides, which grow narrower from the outer to the inner or shackle end of the padlock. The inner curvature B' of the shackle corresponds to the curvature of the concavity in the inner end of the body, the said concavity and inner curvature of the shackle being struck on the same circle and together forming a complete circle within the outline of the design.

I claim—

The design for a padlock as herein shown and described the body and shackle of the bolt forming an oblong figure having rounded ends, and slightly tapering sides which converge from the outer end of the padlock to 35 the inner or shackle-end thereof.

In testimony whereof I have signed this specification in the presence of two subscribing witnesses.

JAMES ROCHE.
